UNITED STATES PATENT OFFICE

164,413

TEAKETTLE

Leonard E. Finch, West Bend, Wis., assignor to
West Bend Aluminum Co., West Bend, Wis., a
corporation of Wisconsin

Application October 7, 1949, Serial No. 5,345

Term of patent 14 years

(Cl. D44—25)

To all whom it may concern:

Be it known that I, Leonard E. Finch, a citizen of the United States, residing at West Bend, in the county of Washington and State of Wisconsin, have invented a new, original, and ornamental Design for a Teakettle, of which the following is a specification, reference being had to the accompanying drawing, forming a part thereof, and in which:

Fig. 1 is a side elevation of a teakettle, showing my new design;

Fig. 2 is a top plan view; and

Fig. 3 is a front elevation of the teakettle.

The dominant features of the design reside in the handle used in combination with a pouring spout and lid therefor on a teakettle of the type disclosed having thin, closely packed annular bands near its base; said handle being characterized by a longitudinally extending rib on its top surface, an attached thumb operated lid opener, and laterally projecting foot portions—all as shown.

I claim:

The ornamental design for a teakettle, as shown and described.

LEONARD E. FINCH.
